US00D568727S

(12) **United States Design Patent** (10) **Patent No.:** **US D568,727 S**
Walker et al. (45) **Date of Patent:** **** May 13, 2008**

(54) **ADJUSTABLE PLANT BOX RAILING
BRACKET**

AU 103831 S 5/1989
CA 97345 12/2002

(75) Inventors: **Simon Walker**, Surrey (CA); **Mark Hopkinson**, Vancouver (CA); **Jianzhong Zhu**, Suzhou (CN); **Wei Min (Karen) Zhu**, Surrey (CA)

Primary Examiner—Gary D. Watson
Assistant Examiner—Susan Bennett Hattan
(74) *Attorney, Agent, or Firm*—Mark Hopkinson

(73) Assignee: **Peak Innovations Inc.**, Richmond, British Columbia

(**) Term: **14 Years**

(21) Appl. No.: **29/277,008**

(22) Filed: **Feb. 9, 2007**

(30) **Foreign Application Priority Data**

Aug. 14, 2006 (CA) 117024

(51) **LOC (8) Cl.** **08-05**

(52) **U.S. Cl.** **D8/380**

(58) **Field of Classification Search** D8/381,
D8/380, 373, 371, 370, 366, 354; 47/40;
248/313, 274.1, 27.8, 231.41, 228.3, 220.41,
248/220.31, 208, 311.2, 217.1, 302, 153;
D12/317; D30/121, 119; D6/566

See application file for complete search history.

FOREIGN PATENT DOCUMENTS

AU 092705 S 7/1986

FIG. 1 is a left side view of a first variant of an adjustable plant box railing bracket;

FIG. 2 is a top view of the first variant of the design;

FIG. 3 is a bottom view of the first variant of the design;

FIG. 4 is a right side view of the first variant of the design;

FIG. 5 is a front side view of the first variant of the design;

FIG. 6 is a rear side view of the first variant of the design;

FIG. 7 is a perspective view of the first variant of the design;

FIG. 8 is a perspective view of the first variant of the design depicted with environmental subject matter;

FIG. 9 is a left side view of a second variant of the design;

FIG. 10 is a top view of the second variant of the design;

FIG. 11 is a bottom view of the second variant of the design;

FIG. 12 is a right side view of the second variant of the design;

FIG. 13 is a front side view of the second variant of the design;

FIG. 14 is a rear side view of the second variant of the design; and,

FIG. 15 is a perspective view of the second variant of the design.

The broken lines in the drawings depict environmental subject matter only and form no part of the claimed design.
